UNITED STATES PATENT OFFICE

152,337

DESIGN FOR A NECKLACE

William W. Hobé, New York, N. Y.

Application October 15, 1948, Serial No. 149,137

Term of patent 3½ years

(Cl. D45—16)

To all whom it may concern:

Be it known that I, William W. Hobé, a citizen of the United States of America, residing in New York city, county of New York, and State of New York, have invented a new, original, and ornamental Design for a Necklace, of which the following is a specification, reference being had to the accompanying drawing, forming part thereof, wherein,

Figure 1 is a front elevational view of a necklace, showing my new design.

Figure 2 is a side elevational view of the necklace shown in Figure 1.

The units of the necklace shown in dotted lines are identical in appearance to their corresponding units shown in solid lines.

I claim:

The ornamental design for a necklace, substantially as shown and described.

WILLIAM W. HOBÉ.
